Primary Examiner—Terry A. Wallace
Attorney, Agent, or Firm—Browning Bushman[57] **CLAIM**

The ornamental design for a handle with hook, as shown and described.

DESCRIPTION

FIG. 1 is a top plan of a handle with hook showing my new design;

1 Claim, 3 Drawing SheetsFIG. 2 is a side elevational view of the handle shown in FIG. 1;

FIG. 3 is an end view taken generally along line 3—3 of FIG. 1;

FIG. 4 is a sectional view taken generally along line 4—4 of FIG. 1;

FIG. 5 is a top plan of a handle with hook;

FIG. 6 is a side elevational view of the handle with hook shown in FIG. 5;

FIG. 7 is an end view taken generally along line 7—7 of FIG. 6;

FIG. 8 is a cross sectional view taken generally along line 8—8 in FIG. 6;

FIG. 9 is a cross sectional view taken through another handle with hook and illustrating an oval cross section, the handle being the same as FIG. 1 except being oval rather than round;

FIG. 10 is a side elevational view of a further handle with hook similar to the handle shown in FIG. 2 but having a rear portion of the handle bent at a slightly decreased angle as compared with the embodiment of FIG. 2; and,

FIG. 11 is a side elevational view of a still further handle with hook similar to the handle shown in FIG. 2 but showing a rear portion of the handle bent at a slightly increased angle as compared with the embodiment shown in FIG. 2.

The broken lines are for illustrative purposes only and form no part of the claimed design.
